UNITED STATES PATENT OFFICE.

LEO S. MILLER, OF DENVER, COLORADO, ASSIGNOR OF ONE-HALF TO BARNEY A. STEINBERG, OF DENVER, COLORADO.

PUMPING APPARATUS.

1,280,519.

Specification of Letters Patent.

Patented Oct. 1, 1918.

Application filed May 15, 1917. Serial No. 168,805.

To all whom it may concern:

Be it known that I, Leo S. MILLER, a citizen of the United States, residing at Denver, in the county of Denver and State of Colorado, have invented certain new and useful Improvements in Pumping Apparatus; and I do hereby declare the following to be a full, clear, and exact description of the invention, such as will enable others skilled in the art to which it appertains to make and use the same.

This invention relates to pumping apparatus, and more particularly to a novel construction of pumps in which there are combined a pump structure and a pressure creating apparatus connected to the pump structure, said apparatus including a pressure accumulating chamber and means for controlling communication between said chamber and the piston cylinder of the pump.

It is one of the objects of the present invention to provide an improved pumping apparatus in which the high pressure generated by the combustion of a combustible gas or vapor can be utilized to act directly upon the movable piston of the pump.

It is a further object of the present invention to provide an improved pump construction in which the pump is provided with a semi-automatic piston designed to control the exhaust of a fluid pressure and to provide in combination with the pump a remote apparatus for compressing a combustible fluid in a pressure accumulating chamber, and from which chamber the high pressure generated by the combustion of the combustible fuel is conveyed to react with a driving impulse on the semi-automatic piston.

A further object of the invention is to provide in combination with a suitable type of pump a combustion chamber and means for charging said combustion chamber with a combustible fuel at suitable pressure, and to provide means for controlling the supply of the pressure generated by the expanding gases at the time of combustion to the pump so that the latter is actuated directly by the force of the ignited fuel.

Among other objects of the invention it is a further purpose to provide an improved type of pump in which there is utilized a piston which is adapted to operate to control the opening of an exhaust port through which the operating fluid delivered into the

piston cylinder of the pump may be exhausted after the piston has made its impulse or operating stroke, and further to provide a pump having a yieldingly supported piston adapted to automatically return under mechanical impulse after the piston has, during its operation, opened the exhaust port to permit the reduction of the impelling pressure from the pump cylinder.

With these and other objects in view the present invention consists in the combination of a suitable type of pump involving a piston and means for generating high pressure and having means for controlling the application of high pressure directly to the piston of the pump.

In the following specification there is described one embodiment of the invention which is illustrated in the accompanying drawings wherein:

Fig. 1 is a general side elevation of the apparatus showing the pump and the pressure generating mechanism as arranged for utilization in remote positions from each other, the connecting means being broken away.

Fig. 2 is a plan view of the apparatus shown in Fig. 1.

Fig. 3 is a side elevation of the compressor and accumulating chamber.

Fig. 4 is a central vertical section in the plane of the axes of the compressor and accumulator.

Fig. 5 is a cross section on line 5—5 of Fig. 4.

Fig. 6 is an enlarged detail sectional view of the pump taken on a vertical diametrical plane through the fluid operating pressure inlet and exhaust connections.

Fig. 7 is a vertical central section through the pump on a plane at right angles to Fig. 6.

Fig. 8 is a transverse section of the pump taken on line 8—8 of Fig. 6.

In the present embodiment of the invention the apparatus is shown as including a suitable form of pressure generator indicated generally at 2, Fig. 1, the generator being connected to an accumulating or combustion chamber 3, this latter being adapted for suitable connection so as to discharge high pressure directly into an appropriate form of pump indicated generally at 4.

One of the broad objects of the present invention is to provide for the utilization di-

rectly of the high pressures generated by the combustion of a combustible fuel in the operation of a pump, and to achieve this purpose I utilize a form of compressor 2 5 shown as including a suitable cylinder 5 within which operates a piston 6 connected by a connecting rod 7 to a crank shaft 8 which may be driven by any suitable means, as, for instance, by power applied to a fly 10 wheel 9 secured appropriately to the shaft 8. When the apparatus is used for the purpose of utilizing the power generated from a combustible fuel or vapor the supply of the latter may be derived from any suitable 15 source and is inducted into the upper end of the compression cylinder 5 through means of an intake valve 10 of suitable type. On the compression stroke of the piston 6 in the compressor a charge of fuel vapor is 20 compressed in a suitable connecting pipe 11 leading from the cylinder 5 into a compression, combustion, or accumulating chamber 12 of the accumulating device 3, the connection 11 preferably being provided with a 25 check valve 13 to prevent the return of pressure from the chamber 12 back into the cylinder of the compressor.

In practice after combustible fuel has been compressed in the chamber 12 to a desired 30 degree the fuel may be ignited through the operation of any suitable igniting device not shown and the high pressure generated therein due to the combustion of the fuel is adapted to be transferred directly to the 35 pump 4 for the operation of a suitable piston therein. To provide for the control of pressure in the combustion chamber 12, and also to provide for the control of the passage of the fluid pressure to the pump 4, 40 there is provided preferably in the combustion chamber 12 a relief valve 15 which is shown as mechanically operated through means of a suitable cam or timing mechanism 16 which in the present instance is 45 geared to the crank shaft 8 of the compressor by a suitable train of gears 17, shown in Fig. 3. While the ratio of the driving gears 17 controlling the operation of the relief valve 15 may be in any suitable proportion, 50 as shown in the present organization the valve 15 is opened once in each four revolutions of the crank shaft 8 thereby permitting the piston 5 of the compressor to make four compression strokes to bring the combustible fuel to the desired degree of compression in the combustion chamber 12, whereupon it may be ignited to cause its expansion and thus produce a high pressure in the combustion chamber whereupon the 55 valve 15 will be opened and the fluid under high pressure permitted to pass from the combustion chamber directly into the pump 4 where it is utilized to operate the piston thereof.

60 65 While the present invention contemplates

the employment of the compression and pressure accumulating mechanism in combination with any suitable form of pump and with a pump which may be located at any desired position relative to the pressure 70 producing mechanism, in the present embodiment of the invention the pump 4 may be of such a type as to be sunk to a suitable depth in a well or other source of fluid to be pumped, and in such installation the 75 pump is connected to the combustion or high pressure chamber 3 through means of a connection as a pipe 3'.

The pump herein illustrated for use in connection with the compression apparatus 80 is illustrated in Figs. 6, 7 and 8 as embodying a casing having a cylindrical outer wall 20 spaced within which there is provided an inner piston cylinder 21 in which operates the piston 22. The pressure supply connection 3' is shown as leading through the outer wall 20 of the casing into the upper end of the piston cylinder 21 at 23 to a point above the head of the piston so that the high pressure produced by the combustion 90 of fuel gases in the high pressure chamber 3 is led directly into the compartment within the cylinder 21 above the piston. When high pressure is admitted to the cylinder 21 through the operation of the relief valve 15 95 the piston 22 is forced downwardly and, as it approaches the limit of its operating or pumping stroke, uncovers an exhaust port 24 located at a suitable point in the length of the cylinder 21 to permit the exhaust of 100 the fluid pressure from above the piston through the exhaust pipe 25.

On its downward stroke the piston causes the displacement of water or other fluid being pumped through a suitable outlet means 105 as an annular series of openings 26 provided at the lower end of the cylinder 21 below the piston 22, the discharged fluid passing through the space between the inner and outer walls 21 and 20 of the pump casing and lifting an eduction valve 27 suitably placed in the pump casing and herein shown as mounted on the head of the pump and controlling the outlet of water through 110 outlet ports 28 in said head. When the 115 pump 4 is installed, for instance, in a well, the natural pressure of the water in the well may act upwardly through openings 29 in the lower head of the pump casing and lift a valve 30 which is slidably 120 mounted on a valve guide pin 31 so that as the piston 22 returns the valve 30 is opened by the pressure of the water outside of the pump casing to replace the water displaced by the downward stroke of the pump. 125 While the pressure of the water outside of the casing may, when passing through the inlet apertures 29 below valve 30, tend to return the piston 22, preferably the latter is mechanically and automatically returned 130

through a suitable means. In the present instance this means is indicated as comprising a spring 32 of suitable strength appropriately disposed between the piston 22 and a convenient fixed portion of or on the casing; in the present instance the spring 32 resting at one end against a seat provided on the upper end of the stem 31 on which the valve 30 is guided, the opposite end of 10 the spring 32 engaging and seating upon the interior face of the head of the piston 22.

It is obvious that the piston 22 may be operated directly by fluid pressure of any 15 nature which may be derived from the source of supply as the high pressure chamber 12, although preferably the pressure is derived from the combustion of a combustible fluid or vapor adapted to be compressed 20 in the combustion chamber through means of the compressing apparatus 2.

From the foregoing it will be seen that in operation of the apparatus suitable combustible vapor is inducted into the compressor 25 above the piston 6 and compressed and discharged by the latter from the compression cylinder into the combustion chamber 12 until it has accumulated to the desired degree of pressure after which it is ignited 30 to burn or explode and is then released through means of the mechanically operated valve 15 to act directly upon the piston 22. This latter in moving downwardly under the impelling force of the pressure 35 fluid is caused to pass the exhaust port 24 at a predetermined time, whereupon the pressure is relieved from above the piston 22 and this latter is returned to its upper position in the cylinder 21 through means 40 of the automatically operating device or spring 32 which in some instances may be aided by the pressure of the fluid within the well or other position in which the pump may be mounted.

45 When the compressing apparatus is of the type designed to compress a fuel vapor and in which the latter is consumed by combustion and high pressure created, if desired the compressor 2 and the combustion or 50 high pressure apparatus 3 may be provided with suitable water jackets as indicated at 2' and 3', Fig. 4. An advantage of this type of construction is that when the pumping apparatus involves a pump 55 structure adapted to be mounted in a well or other position in which the pump mechanism would be located so as to cause difficulty in gaining access thereto, by the present invention one portion of the apparatus may be lowered into the well or other position, while the compressing and pressure producing mechanism may be located at a convenient position at the top 60 of the well or other station to be readily 65 accessible by the operator for the renewal

or adjustment of the mechanism as may be necessary.

What is claimed as new is:

1. In pumping apparatus, a pump cylinder, a yieldingly supported piston therein, 70 a pressure accumulating chamber, and means controlling communication between said chamber and the cylinder above the piston.

2. In pumping apparatus, a pump cylinder, a piston therein, a combustion chamber 75 connected to said cylinder above the piston, and means controlling communication therebetween.

3. In pumping apparatus, a pump cylinder, a yieldingly supported piston therein, a 80 combustion chamber connected to said cylinder above the piston, and means controlling communication therebetween.

4. In pumping apparatus, a pump cylinder having induction and eduction valves, 85 a piston in said cylinder, a pressure accumulating chamber communicating with said cylinder, means for controlling said communication, and compressing means for storing fluid pressure in said chamber. 90

5. In pumping apparatus, a pump cylinder and its piston, induction and eduction valves for the cylinder, a pressure accumulating chamber connected to said cylinder, a valve for controlling communication therebetween, and compressing means connected to said chamber and having timed relation to 95 said valve.

6. In pumping apparatus, a pump cylinder and its piston, a combustion chamber 100 having valved communication with said cylinder above the piston, means for compressing a combustible charge in said chamber, and means for admitting the high pressure of combustion directly from said chamber to 105 the cylinder for action on the piston.

7. A pump having, in combination, a pressure accumulating chamber, a fluid intake chamber, a fluid outlet chamber related thereto, and means controlling the admission 110 of the accumulated pressure to the intake chamber for the expulsion of the fluid therein.

8. In a pump, the combination of a casing having a valved intake chamber and a valved outlet chamber for fluid, a combustion engine, an accumulator for gases from the engine, and means for controlling the admission of the pressure from said accumulator to the intake chamber to expel the fluid 115 therefrom.

9. Pumping apparatus having a combustion chamber, a cylinder, having a pressure inlet from said chamber, and an exhaust port, and a piston actuated by pressure from 120 said chamber and controlling exhaust from the cylinder.

10. Pumping apparatus having a combustion chamber, a cylinder, having a pressure inlet from said chamber, and an exhaust 125

- port, and a piston actuated by pressure from said chamber and controlling exhaust from the cylinder, and means for automatically returning the piston.
- 5 11. A pump comprising a casing having an inner cylinder with a pressure inlet at one end and an exhaust port in its side, and a piston operative by pressure in said cylinder and controlling the exhaust at said port.
- 10 12. A pump comprising a casing having an inner cylinder with a pressure inlet at one end and an exhaust port in its side, a piston operative by pressure in said cylinder and controlling the exhaust at said port, and induction and eduction ports and their valves in said casing.
- 15 13. A pump comprising a casing having an inner cylinder with a pressure inlet at one end and an exhaust port in its side, and

an automatic piston operative by pressure in 20 said cylinder and controlling the exhaust at said port.

14. A pump comprising a casing having an inner cylinder and a piston therein, pressure inlet and exhaust ports for the cylinder, 25 the latter controlled by the piston, valved intake ports on one head of the casing and opposed to the piston, and valved outlets in the casing.

15. A pump comprising a casing having 30 a cylinder and a piston therein, a pressure inlet at one end of the cylinder, exhaust means in the cylinder wall, and means for automatically returning the piston after its pumping stroke and after exhaust of operating, fluid pressure in the cylinder.

In testimony whereof I affix my signature.

LEO S. MILLER.
